UNITED STATES PATENT OFFICE

ANDREW G. McNICOLL, OF MINNEAPOLIS, MINNESOTA, ASSIGNOR TO MINNEAPOLIS-HONEYWELL REGULATOR COMPANY, OF MINNEAPOLIS, MINNESOTA, A CORPORATION OF DELAWARE

DESIGN FOR A CLOCK THERMOSTAT

Application filed January 28, 1932. Serial No. 42,651. Term of patent 14 years.

To all whom it may concern:

Be it known that I, ANDREW G. McNICOLL, a citizen of the United States, residing at Minneapolis, in the county of Hennepin and State of Minnesota, have invented a new, original, and ornamental Design for Clock Thermostat, of which the following is a specification, reference being had to the accompanying drawings, forming part thereof.

Fig. 1 is a front elevation of a clock thermostat, showing my new design;

Fig. 2 is a side elevation;
Fig. 3 is a bottom plan; and
Fig. 4 is a top plan.

I claim:

The ornamental design for a clock thermostat as shown.

In witness whereof, I have hereunto set my hand at Minneapolis, Minn., this 25th day of January, A. D. one thousand nine hundred and thirty-two.

ANDREW G. McNICOLL.
